UNITED STATES PATENT OFFICE.

HUMPHREY THOMAS LOGAN, OF PUTNEY, ENGLAND.

MECHANISM FOR HANDLING GOODS.

1,173,819.

Specification of Letters Patent.

Patented Feb. 29, 1916.

Application filed May 3, 1915. Serial No. 25,437.

To all whom it may concern:

Be it known that I, HUMPHREY THOMAS LOGAN, a subject of the King of England, residing at Putney, Surrey, England, have 5 invented certain new and useful Improvements in Mechanism for Handling Goods, of which the following is a specification.

This invention is for improvements in or relating to mechanism for handling goods 10 and has for its object to provide an inexpensive form of apparatus particularly suitable for advertising purposes which may take the form of the figure of a human being which picks up goods to be vended or distributed and holds them out to persons to take.

It has been proposed to provide an automatic figure, resembling a human being, with a movable forearm driven by mechanical means and controlled electrically. Cards were delivered to a fixed hand of the figure and the hand of the movable fore-arm was moved against the card in such manner that this was thrust between the finger and 25 thumb of the hand thus breaking an electrical contact previously established between these two parts. The mechanism then moved the fore-arm to swing the hand out and away from the fixed arm into an out-stretched position where it would remain until the card being withdrawn, the electrical contact was again established between the thumb and the finger and the operation repeated.

According to this invention there is combined with a member (for example the arm and hand of a figure) for engaging and transferring goods, mechanism for positively moving the member into contact with the goods and a reversing element in the 40 train of such mechanism for positively moving the member in the opposite direction, and pneumatic means for attaching the goods to the member but not transferring them when the latter is brought into contact with the same and for simultaneously operating the reversing element so that the member will be positively moved back with the goods attached thereto. It is known to 45 employ suction arms, mechanically controlled, to pick up a card from a pile and transfer it to a receptacle, and it is also known in the printing art to pick up a sheet from a pile of sheets by a pneumatic plunger 50 which drops by gravity on to the sheet and

then returns by suction to lift the sheet prior to its being gripped by feeders to carry it forward. In this latter device the plunger is made to rise by suction which is maintained upon it at all times, but only becomes 60 operative for raising the plunger when a suction orifice at the bottom of the plunger is closed by a sheet being sucked on to the end of the plunger.

The means for engaging the goods may 65 take the form of a suction device communicating with a suction cavity at the point of contact between the member and the goods and automatic valves may be provided in the suction device so that when the cavity is 70 closed the valves operate to apply the suction to move a controlling member, say a bellows for the driving gear, in one direction, and when the suction cavity is open, the valves operate to apply the suction to 75 move the said controlling member in the opposite direction.

In the accompanying drawings which illustrate one method of carrying out this invention, Figure 1 is a perspective view in 80 part section showing the invention as applied to an automatic figure for handing out leaflets, Fig. 2 is a diagrammatic view of certain details of Fig. 1 shown in part section, Fig. 3 is a diagrammatic view of the 85 main parts of a vending machine for co-operation with an automatic figure, such as is shown in Fig. 1, Fig. 4 is a diagram indicating the movements of one of the parts in Fig. 3, Fig. 5 is another diagram indicating the movements of the picking up and transferring member, and Fig. 6 is a diagrammatic view of part of the arm of the 90 automatic figure constructed according to a modification of the present invention. 95

The same letters indicate the same parts throughout the accompanying drawings.

The automatic figure indicated at A, Fig. 1, may be made up in any convenient manner and in itself constitutes no part of the present invention. The only movable part is the hand and arm A¹ which constitutes the picking-up and transferring member. The figure is shown as carrying a box A² in which is a pile of leaflets A³, and the figure 100 in the example shown is arranged to pick up a leaflet and hold it in the position shown in dotted lines at the left of Fig. 1.

Within a casing B on which the automatic figure stands is an electric motor B¹ which 105

drives a shaft B^2 through any suitable reducing gear (not shown in the drawings), which may be contained in the casing of the motor. The shaft B^2 constitutes the inner shaft of a differential gear. Carried by the shaft B^2 are two studs C on which are mounted the intermediate wheels C^1 of the differential gear, and these mesh with the usual miter-wheels C^2 , C^3 respectively. The wheel C^2 is carried by a short hollow shaft C^4 mounted free on the shaft B^2 , and fast on this is a miter-wheel D . This wheel D meshes with a miter-wheel D^1 fast on a spindle D^2 . The spindle D^2 is rotatably mounted in a plate E and has fast on it on that side of the plate remote from the wheel D^1 a wheel E^1 . The means for supporting the spindle D^2 are not shown in detail in the drawings, as such details in themselves constitute no part of the present invention.

The plate E can rock about the axis of the wheel E^1 , that is about the spindle D^2 , and has an arm E^4 whereby it is connected to a controlling member, hereinafter further described, whereby it is rocked as required. The plate carries two intermediate wheels E^2 , E^3 ; the wheel E^2 is in mesh with the wheel E^1 and the wheel E^3 is in mesh with the wheel E^2 . Near the wheels E^2 , E^3 is a wheel F which is carried at the end of a vertical shaft F^1 which extends up through one leg of the figure A, and carries at its upper end a skew toothed wheel F^2 . The plate E with the wheels E^2 , E^3 thereon is so positioned relatively to the wheel F that when rocked in one position the wheel E^2 meshes with the wheel F , and when rocked in the opposite direction the wheel E^3 meshes with the wheel F , and the wheel E^2 is moved out of gear.

Rotatably mounted in a fixed support G within the figure A is a spindle G^1 . This has at one end a skew toothed wheel G^2 which gears with the skew toothed wheel F^2 , and at the other end a bevel wheel G^3 which meshes with a bevel wheel H rotatably mounted on a stud, not shown in the drawings, fixed to an extension G^4 of the support G . Fast on this wheel is the member A^1 which conveniently takes the form of a rod covered with the molded arm and hand. A spring A^4 is fixed rigidly at one end to the extension G^4 of the support G and engages the rod A^1 at the other end. This spring is so positioned and tensioned that it tends always to bring the arm or member A^1 to a vertical position, that is one which is midway between that which the arm is shown as occupying and that indicated by dotted lines at the left of Fig. 1.

The wheel C^3 is carried by a shaft J whose other end has fast on it a miter-wheel J^1 which meshes with a miter-wheel J^2 . Fast on the wheel J^2 is a smaller miter-wheel J^3 which engages a larger wheel J^4 . This

wheel J^4 is operatively connected in any convenient manner with bellows J^5 for maintaining suction on two conduits J^6 and J^7 respectively. The conduit J^7 extends up through the automatic figure A 70 and through the movable arm of the same to a cup A^5 secured in the palm of the hand and constituting part of the member A^1 . The conduit J^6 communicates with a chamber K^1 in a valve-chest K . 75 In this chest are two valves L and M respectively. The valve L is carried by a diaphragm L^1 stretched over an opening in the base of the chamber K^1 , and the valve M is carried by a diaphragm M^1 stretched over 80 an opening in the base of the chamber K^1 . These openings do not communicate direct with the atmosphere, but the opening covered by the diaphragm L^1 communicates with one end of a conduit L^2 whose other 85 end traverses a central projection A^6 in the cup A^5 , the end of the conduit being open to the atmosphere at the end of the projection. There is, moreover, a bleed-hole L^3 permanently communicating between the 90 chamber K^1 and the conduit L^2 .

The valve L is a double valve controlling a conduit N . One end of this conduit communicates with the cavity under the diaphragm M^1 , and the other end is connected by a tube N^1 to one side of a pair of bellows O , O^1 . The tube N^1 is connected at N^2 to the bellows O^1 and the bellows O are connected at N^3 through a tube N^4 to a chamber N^5 in which the valve M is 100 mounted.

The valve L covers one of two ports N^6 N^7 according to its position, that is to say when it is lowered as shown in the drawing, it covers the port N^6 (which, if uncovered, would put the conduit N into communication with the atmosphere) and uncovers the port N^7 which throws the conduit N into communication with the chamber K^1 . Similarly the valve M controls two ports M^2 , M^3 respectively, the port M^2 when opened throwing the chamber N^5 into communication with the atmosphere, and the port M^3 when opened putting the chamber N^5 into communication with the chamber K^1 . With the valve M in the position shown in the drawing, the port M^3 is closed and M^2 is open. The bellows O , O^1 are connected by a link O^2 to the arm E^4 of the plate E .

The operation of this device is as follows: The motor drives the shaft B^2 of the differential gear C — C^3 , and this rotates the shafts J and C^4 . The shaft C^4 rotates the shaft F^1 which extends up through the leg of the figure A, the connection of the two shafts being through the wheels D , D^1 , E^1 , E^2 and F , or E^1 , E^2 , E^3 , and F , according to the position of the plate E as hereinafter explained. The shaft F^1 is not always moving, and when stationary the 130

wheels by which it is driven, including the wheel C^2 of the differential gear, remain stationary, and then all the drive of the shaft B^2 is transmitted to the shaft J . This 5 shaft operates the suction bellows J^5 through the gear-wheels J^1-J^4 and as the shaft is always rotating, the bellows maintain a certain degree of suction upon the conduits connected with them. The conduit J^7 makes 10 direct connection from the bellows to the larger cavity A^5 in the hand of the figure, so that air is always being drawn in through this conduit, unless the cavity is covered.

In Fig. 2 the parts are shown in the position occupied when the hand is covered by one of the leaflets A^3 , and for the purpose of describing the operation, it will be presumed that the arm is in the position shown in dotted lines in Fig. 1 and the 15 leaflet A^3 resting thereon. The leaflet not only covers the cavity A^5 , but also the cavity in the projection A^6 , so that the pressures on the opposite sides of the diaphragm L^1 balance each other; that is the suction in 20 the chamber K^1 exhausts the conduit L^2 through the bleed-hole L^3 and thus the valve L can drop into the position shown in the drawing, leaving the port N^7 open and the port N^6 closed. This puts the conduit N 25 into communication with the suction conduit J^6 and thus the bellows O^1 is exhausted and thereby collapsed, so that the plate E has been rocked by the arm E^4 about the axis of the spindle D^2 in a clockwise direction, and the wheel E^2 brought into mesh 30 with the wheel F . This wheel rotates the shaft F^1 in the direction to bring the arm and hand A^1 of the automatic figure from the position shown in Fig. 1 in full lines 35 to that shown in dotted lines. As soon as the arm has reached the outstretched position shown in dotted lines, the mechanism driving it stops, because the arm cannot move farther than to the position indicated, 40 any convenient means, not shown in the drawings, being provided to check it at this point. Thus the hollow shaft C^4 of the differential gear and all the parts which it drives will be stopped, but the shaft J will 45 continue to rotate. The suction is thus maintained upon the leaflet on the hand of the automatic figure, and no further movement of the automatic figure takes place until the leaflet is removed. If the device 50 is used as an advertising device outside, say, a shop or store, the figure will thus remain stationary until someone pulls the leaflet off the hand, when atmospheric pressure being thus admitted to the cavity in the 55 projection A^6 , the position of the valves L and M will be immediately automatically reversed, that is atmospheric pressure will be admitted to the side of the diaphragm L^1 at which the conduit L^2 communicates, 60 and the bleed-hole L^3 will thus no longer be

able to maintain equal pressures on both sides of the diaphragm. The diaphragm will thus be forced up, closing the port N^7 and opening the port N^6 to atmosphere. This admits atmospheric pressure to the 70 conduit N so that the diaphragm M^1 is also forced up, causing the valve M to close the port M^2 and open the chamber N^5 to the chamber K^1 and thus to the suction pipe J^6 . The admission of atmospheric pressure to the conduit N also admits it to the bellows O^1 , and the connecting of the conduit N^4 with the chamber K^1 shuts off the bellows O from connection with the atmosphere and the air is therefore immediately 75 exhausted from the bellows O , while air simultaneously is admitted to the bellows O^1 . This causes a sharp movement of the bellows to the right of Fig. 2, causing the plate E to be rocked in a counter-clockwise 80 direction which brings the wheel E^2 out from engagement with the wheel F and brings the wheel E^3 into engagement therewith. The driving mechanism from the shaft C^4 is now no longer locked, because 85 the wheel E^3 tends to rotate in the reverse direction to that of the wheel E^2 and thus tends to drive the wheel F and its shaft F^1 in the reverse direction to that in which it was previously moved, and the arm A^1 , although locked against further movement in 90 the one direction, is free to move back into the position shown in full lines in Fig. 1. The arm A^1 thus immediately swings back until it is brought into contact with the 95 pile of leaflets A^3 , when one is again sucked up against the hand covering the cavity in the projection A^6 , thus allowing the bleed-hole L^3 to once more balance the pressures 100 on the opposite side of the diaphragm L^1 . 105 The valve L will then immediately drop into the position shown in Fig. 2, putting the conduit N into communication with the chamber K^1 , which will balance the diaphragm M^1 and cause the valve M to drop, and thus suction is applied to the bellows O^1 again and atmospheric pressure admitted 110 to the bellows O , so that they once more move over to the position shown in Fig. 2 and cause the wheel E^2 to be brought into 115 mesh with the wheel F and the wheel E^3 to be moved out from engagement therewith. The arm A^1 is now again moved over to the stretched-out position shown in dotted lines in Fig. 1 and remains there 120 until the leaflet once more is removed from the hand of the automatic figure, when the operation will be again repeated.

Obviously the hand of the automatic figure may be made to pick up articles as well 125 as leaflets. For example, it may be employed to deliver packets of chocolates or other articles fed out from an automatic vending machine. Fig. 3 shows diagrammatically how the parts of an automatic 130

vending machine would be arranged for this purpose. It would not be desirable to have a motor continuously running, as a vending machine is not always in use, and although the motor could be automatically switched on and off as required, it would constitute an expensive element in the machine so that other means for effecting the drive of the shaft F^1 and for creating the requisite suction upon the valve-box K and other parts is preferred. Extending out through the casing B of the machine is the end of an operating lever P^1 . This is pivoted at P^2 and has on it a series of ratchet-teeth P^3 which coöperate with a pawl P^4 controlled by a spring P^5 . That end of the pawl remote from the end which coöperates with the ratchet-teeth P^3 is extended at P^6 beyond the point of pivoting of the ratchet which is at P^7 and engages a tail-piece P^8 of a long lever P^9 which is pivoted at P^{10} . The lever P^9 carries at its free end a tilting plate P^{11} which lies opposite a guide P^{12} from a coin-slot P^{13} . The plate P^{11} has a lip P^{14} at that end remote from the guide P^{12} so that the coin can slide down the guide onto the plate and is arrested by the lip P^{14} . The lever P^9 further has pivoted to it at P^{15} a pending rod P^{15} whose end rests over the movable end of a pair of bellows Q . The bellows are controlled by a spring Q^1 and have communicating with them the two conduits J^6 , J^7 ; these are covered by a valve Q^2 inside the bellows which prevents air from being driven through them, and the bellows are provided with an outlet valve Q^3 whereby the air may escape from the bellows when they are collapsed by the rod P^{15} . The rod P^{15} has a laterally projecting pin P^{16} which engages an arm R^1 on a toothed quadrant R which is pivoted at R^2 . The quadrant engages a toothed wheel R which is engaged with its shaft with a pawl-and-ratchet R^4 , R^5 , the ratchet being fast on the shaft R^{10} and the pawl carried by the wheel. The shaft R^{10} carries a second toothed wheel R^6 which meshes with a miter-wheel R^7 , and this in turn meshes with a second miter-wheel R^8 fast on the shaft D^2 ; the miter-wheel R^8 thus takes the place of the wheel D^1 on the shaft D^2 . The quadrant R is controlled by a spring R^9 which always tends to drive the quadrant downward in the direction shown by the arrow, and this spring is sufficiently powerful to drive the shaft D^2 , connected through the reversing mechanism to the shaft F^1 (not shown in this figure) and cause the automatic figure A shown in Fig. 1 to perform the evolutions already described. The lever P^1 may also be employed to discharge the chocolate or other article indicated at S , and for this purpose works in a stirrup S^1 hung from a bell-crank lever S^2 pivoted at S^3 and having connected to it a push-rod S^4 . The push-rod enters the bottom of a chamber S^5 in which the pile of chocolates S is stored, and an opening S^6 is provided in the chamber opposite the push-rod S^4 so that when the rod is advanced the bottom chocolate can be pushed out on to a delivery-plate S^7 .

The operation of this device is as follows: When a coin is put in the slot P^{13} it falls upon the tray P^{11} and depresses the end of the lever P^9 so that the pawl is moved against the action of its spring P^5 and is disengaged from the tooth P^3 of the operating lever P^1 . The lever P^1 being thus released can then be depressed by hand by the person who desires to obtain an article from the vending machine, and in depressing the lever the bellows Q are depressed and the quadrant R is raised so that its lower end is in mesh with the wheel R^3 . The depression of the lever P^1 will also cause the bell-crank lever to be rocked by means of the stirrup S^1 , so that the push-rod S^4 discharges a chocolate from the chamber S^5 on to the guide-plate S^7 to the bottom of which it slides down, and the bottom portion lies in the position to which the hand of the automatic figure A is brought when the figure operates. When the lever P^1 is fully depressed a stud p thereon is brought into contact with the end of the tray P^{11} and tilts it so that the coin falls out of the tray into a receptacle p^1 provided to receive it. The lever P^1 is now released and is thus free to return and as the lever P^9 no longer carries the coin, the pawl P^4 falls into position to engage the ratchet-teeth P^3 of the lever. The bellows Q now begin to expand under the action of their spring Q^1 and this creates suction on the conduits J^6 , J^7 and the quadrant R being released from the pin P^{16} as the lever P^1 rises, begins to drive the wheels R^3 , R^6 , R^7 , R^8 so that the motive power is supplied for moving the shaft F^1 and the arm of the automatic figure in the manner already described. The operation of the valve in the valve-box K^1 with which the conduit J^6 communicates is the same as that already described, and the automatic figure picks up the article from the tray S^7 and holds it out to the purchaser. As soon as the purchaser removes it, the arm returns and the mechanism stops.

It will be appreciated that it is desirable that no part of the mechanism shall be allowed to start its operations until the lever P^1 has been fully depressed, as otherwise there might not be sufficient suction or driving power stored up at the start to effect all the necessary operations. For this purpose a wheel T may be geared in any convenient manner to the shaft F^1 so that it rotates through the same angular distance as the shaft. This wheel has on it a cam-tooth T^1 , the toothed side of the cam being engaged by a claw T^2 on the lever T^3 pivoted at T^4 . The

lever T^3 has a second claw T^5 on it which lies clear of the path of the tooth T^1 when the claw T^2 is in the path of the tooth. The end of the lever T^3 is engaged by a pin T^{17} 5 on the rod P^{15} when the lever P^1 is pushed down.

The operation of this mechanism is as follows: When the parts are at rest the cam-tooth T^1 rests against the claw T^2 , as shown 10 in Fig. 3, the wheel T tending to drive in the direction of the arrow. This holds the mechanism in such position that the arm of the figure is approximately vertical, as shown at position 1 in Fig. 5, and as the 15 operating lever P^1 is depressed no part of the automaton can be set in operation until the pin P^{17} lifts the claw T^2 out of the path of the tooth T^1 . The wheel T will then advance until its tooth T^1 is brought to the 20 position shown at 2, Fig. 4, and this will bring the arm from the position 1 to the position 2, Fig. 5, where it picks up the goods to be transferred from the tray S^7 and presented to the purchaser. The automatic reversing 25 mechanism then operates and the arm is swung back from the position 2 past the position 1 to the position 3, and the tooth T^1 of the wheel T travels similarly past the position 1 to the position 3 shown in Fig. 4. 30 In coming to the position 3, however, it passes under the claw T^5 and the cam side of the tooth pushes the claw back, so that the lever T^3 is once more in position ready to catch the tooth T^1 . As soon, therefore, as 35 the goods are removed from the hand of the automatic figure the arm A^1 commences its return movement, but on reaching the position 1, it is stopped because the tooth T^1 engages the claw T^2 and arrests the whole 40 mechanism.

An interesting feature about this automatic figure is that if the article to be picked up is not at first correctly laid hold of the arm moves back to again pick it up, that is 45 to say, if the goods on the tray do not always occupy the same position so that when the hand comes down on the packet the cavity A^5 therein is not quite covered, the arm will sometimes commence to return and then 50 the packet drop, whereupon the automatic reverse mechanism will immediately operate and the hand returns again to pick up the packet. Each attempt to pick the packet up, however, draws the packet more toward 55 the position which the hand occupies, and consequently it finally secures the packet and transfers it to the delivery position. The quadrant R is of course made of sufficient length to allow for these minor return 60 movements, and the claw T^2 does not prevent them, because the tooth T^1 will during such intervals be merely oscillating between the positions 1 and 2 of Fig. 4 and never moving far from the position 2 so that the 65 tooth does not come into contact with the

claw T^5 until the packet has been properly secured and the arm moves right over to the position 3 of Fig. 5.

Instead of using the automatic figure to hand out articles or leaflets, it may be employed to turn over the pages of a book. In Fig. 6 a book is indicated at U and the movable arm of the figure is in this case made up of two movable parts, one part V which is secured to the bevel toothed-wheel H as 70 before, the other part V^1 being hinged to the part V at V^2 and normally kept in line therewith by a spring V^3 , the joint at V^2 being such as to prevent movement of the part V^1 beyond the straight line position 75 with the part V . On the part V^1 is a lateral arm V^4 which carries a roller V^5 and carried by any convenient fixed part of the figure is a stationary stop W . The stop lies in the path of the roller V^5 when the arm V , V^1 80 is moved over to the delivery-position, but there is no stop to coöperate with the roller when in the picking-up position. Thus when the arm is in the position to the right of Fig. 6 indicated in dotted lines it engages the 85 page of the book, and then swings over, being operated as has been described with reference to Figs. 1 and 2, so that the page is brought over to the left of the figure, the arm being still in engagement with it as 90 shown by dotted lines on that side; just as it reaches this position the roller V^5 strikes upon the top of the pin W and is thereby thrust laterally aside, the roller acting as a cam, so that the arm is pulled sidewise 95 into the position shown in full lines in Fig. 6. This lateral movement, which is effected somewhat quickly, disengages the arm from the page so that the mechanism will immediately move it over to the right-hand side of 100 Fig. 6 to pick up the next page, and this operation will be repeated continuously. 105

What I claim as my invention and desire to secure by Letters Patent is:—

1. The combination of a member for engaging and transferring goods, actuating mechanism for positively moving the member into contact with the goods, a reversing element in the train of such mechanism for positively moving the member in the opposite direction, pneumatic means for attaching the goods to the member when the latter is brought into contact with the same, and further pneumatic means controlled by the first mentioned pneumatic means for automatically operating the reversing element as soon as the goods are attached so that the member will be positively moved back by the aforesaid actuating mechanism with the goods attached thereto; substantially as 115 described.

2. The combination of the arm and hand of a figure for engaging and transferring goods, actuating mechanism for positively moving the arm into contact with the goods, 120

3. reversing element in the train of such mechanism for positively moving the arm in the opposite direction, pneumatic means for attaching the goods to the arm when the latter is brought into contact with the same, and pneumatic means controlled by the first mentioned pneumatic means for automatically operating the reversing element as soon as the goods are attached so that the arm will be positively moved back by the aforesaid actuating mechanism with the goods attached thereto, substantially as described.
4. The combination of a member for engaging and transferring goods which is moved in a curved path, actuating mechanism for positively moving the member into contact with the goods, a reversing element in the train of such mechanism for positively moving the member in the opposite direction, pneumatic means for attaching the goods to the member when the latter is brought into contact with the same, and pneumatic means controlled by the first mentioned pneumatic means for automatically operating the reversing element as soon as the goods are attached so that the member will be positively moved back by the aforesaid actuating mechanism with the goods attached thereto; substantially as described.
5. The combination of a member for engaging and transferring goods which is moved in a curved path to first lift the goods and then transfer them to a point to one side of the point whence they are lifted, actuating mechanism for positively moving the member into contact with the goods, a reversing element in the train of such mechanism for positively moving the member in the opposite direction, pneumatic means for attaching the goods to the member when the latter is brought into contact with the same, and pneumatic means controlled by the first mentioned pneumatic means for automatically operating the reversing element as soon as the goods are attached so that the member will be positively moved back by the aforesaid actuating mechanism with the goods attached thereto; substantially as described.
6. The combination of the arm and hand of a figure for engaging and transferring goods, a vertical driving shaft (F^1) passing up through the body of the figure, a second shaft in the upper arm of the figure geared to the vertical shaft and lying at an angle thereto, a support (G, G^4) in the upper arm of the figure whereon the forearm is pivoted, toothed gearing operatively connecting the second shaft with the forearm, mechanism including a reversing element for driving the shaft (F^1), pneumatic means for attaching the goods to the forearm when the latter is brought into contact with the same and further pneumatic means controlled by the first mentioned pneumatic means for automatically operating the reversing element as soon as the goods are attached so that the forearm will be positively moved back by the aforesaid driving shaft and its actuating mechanism with the goods attached thereto; substantially as described.
7. The combination of the arm and hand of a figure for engaging and transferring goods, a vertical driving shaft (F^1) passing up through the body of the figure, a second shaft in the upper arm of the figure geared to the vertical shaft and lying at an angle thereto, a support (G, G^4) in the upper arm of the figure whereon the fore-arm is pivoted, toothed gearing operatively connecting the second shaft with the forearm, a centralizing spring (A^4) for the said fore-arm, mechanism including a reversing element for driving the shaft (F^1), pneumatic means for attaching the goods to the fore-arm when the latter is brought into contact with the same and further pneumatic means controlled by the first mentioned pneumatic means for automatically operating the reversing element as soon as the goods are attached so that the fore-arm will be positively moved back by the aforesaid driving-shaft and its actuating mechanism with the goods attached thereto; substantially as described.
8. The combination of a member for en-

gaging and transferring goods, a controlling-member, actuating mechanism for the aforesaid transferring member comprising a driving-wheel (E¹), a driven wheel (F) 5 geared to the transferring member, a plate (E) pivoted about the axis of the driving wheel (E¹), two intermediate wheels (E² E³) carried on the plate and operatively connected with the driving-wheel in such 10 manner as to rotate in opposite directions, operative connection between the said plate and the above mentioned controlling-member to move the plate and thus bring one or other of its two wheels (E² E³) into mesh 15 with the driven wheel (F) according to the direction in which it is moved by the controlling member, pneumatic means for attaching the goods to the transferring member when the latter is brought in contact 20 therewith, and further pneumatic means controlled by the first mentioned pneumatic means for automatically actuating the controlling member as soon as the goods are attached so that the transferring member 25 will be positively moved back by the aforesaid actuating mechanism with the goods attached thereto; substantially as described.

9. The combination of a member for engaging and transferring goods, coin-freeed 30 actuating mechanism for positively moving the member into contact with the goods, a reversing element in the train of such coin-freeed mechanism for positively moving the member in the opposite direction, pneumatic 35 means for attaching the goods to the member when the latter is brought into contact with the same and further pneumatic means controlled by the first mentioned pneumatic means for automatically operating the 40 reversing element as soon as the goods are attached so that the member will be positively moved back by the aforesaid actuating mechanism with the goods attached thereto; substantially as described.

45 10. In an automatic vending machine, the combination of a member for engaging and transferring goods, actuating mechanism for positively moving the member into contact with the goods, a reversing element in 50 the train of such mechanism, a spring-driven rack (R) for operating the said member through the train of actuating mecha-

nism, pneumatic means for attaching the goods to the member when the latter is brought into contact with the same, further 55 pneumatic means controlled by the first mentioned pneumatic means for automatically operating the reversing element as soon as the goods are attached so that the member will be positively moved back by the aforesaid actuating mechanism with the goods attached thereto, a spring-driven suction-device (Q) for providing the pneumatic power, and a coin-freeed loading lever (P¹) operatively connected with these devices to 60 return them to their starting positions and load their springs prior to each operation; substantially as described.

11. In an automatic vending machine the combination of a member for engaging and 70 transferring goods, actuating mechanism for positively moving the member into contact with the goods, a reversing element in the train of such mechanism, pneumatic means for attaching the goods to the member when the latter is brought into contact 75 means controlled by the first mentioned pneumatic means for automatically operating the reversing element as soon as the goods are attached so that the member will 80 be positively moved back by the aforesaid actuating mechanism with the goods attached thereto, a coin-freeed operating lever for the said actuating mechanism, a wheel (T) geared with the transferring member, a 85 cam-tooth (T¹) with a locking face on one side on the said wheel, a pivoted catch which co-operates with the cam-tooth (T¹) to hold the wheel and with it the transferring member against movement, means whereby when 90 the operating lever of the vending machine is displaced to the full limit of its movement the catch is tripped to free the tooth, and means whereby the tooth during its movement replaces the catch to again lock 95 the wheel at the end of the cycle of movements; substantially as described.

In testimony whereof I have signed my name to this specification in the presence of two subscribing witnesses.

HUMPHREY THOMAS LOGAN.

Witnesses:

A. M. HAYWARD.
